Primary Examiner—Holly Baynham

[57] CLAIM

The ornamental design for a snow shovel, as shown and described.

DESCRIPTION

FIG. 1 is a front elevation view of a snow shovel embodying my invention;

FIG. 2 is a rear elevation view of the snow shovel shown in FIG. 1 and embodying my invention;

FIG. 3 is a side elevation of the right side of the snow shovel illustrated in FIG. 1 and embodying my invention; the left is a mirror image of the right;

FIG. 4 is a perspective view of the snow shovel shown in FIGS. 1 through 3 and embodying my invention;

FIG. 5 is a top plan view relative to FIG. 3 of the snow shovel illustrated in FIGS. 1 through 4 and embodying my invention; and,

FIG. 6 is a bottom plan view relative to FIG. 3 of the snow shovel illustrated in FIGS. 1 through 5 and embodying my invention.

The broken line showing of a fragmented shovel handle is for illustrative purposes only and forms no part of the claimed design.
